(57) **CLAIM**

The ornamental design for pair of earbuds, as shown and described.

DESCRIPTION

FIG. 1 is a perspective view of the left and right earbud of the pair of earbuds showing our new design, the cord is drawn broken away for purposes of illustration;

FIG. 2 is a top plan view of the left earbud shown separately for purposes of illustration, the top plan view of the right earbud being a mirror image thereof;

FIG. 3 is a front elevational view of the left earbud, the front elevational view of the right earbud being a mirror image thereof;

FIG. 4 is a right side elevational view of the left earbud, the right side elevational view of the right earbud being a mirror image thereof;

FIG. 5 is a left side elevational view of the left earbud, the rear elevational view of the right earbud being a mirror image thereof; and,

FIG. 6 is a rear elevational view of the left earbud, the rear elevational view of the right earbud being a mirror image thereof; and,

FIG. 7 is a bottom plan view of the left earbud, the bottom plan view of the right earbud being a mirror image thereof. The broken lines showing of the environment in FIGS. 1-7 are for illustrative purpose only and form no part of the claimed design.

1 Claim, 3 Drawing Sheets
